UNITED STATES PATENT OFFICE.

JOSEPH JORDAN RIGGSBEE, OF DURHAM, NORTH CAROLINA.

MANICURING DEVICE.

Application filed September 8, 1928. Serial No. 304,651.

This invention relates to a manicuring device, one of the objects being to provide a simple and compact structure utilizing a sheet of abrasive material which can be replenished at will, simple means being employed for holding the material in proper position where either of two faces are exposed for use.

With the foregoing and other objects in view the invention resides in the combination and arrangement of parts and in the details of construction hereinafter described and claimed it being understood that changes in the precise embodiment of the invention herein disclosed may be made within the scope of what is claimed without departing from the spirit of the invention.

In the accompanying drawings the preferred form of the invention has been shown. 20 In said drawings, Figure 1 is a plan view of the device. Figure 2 is a section on line 2—2, Figure 1. Figure 3 is a section on line 3—3, Figure 2. Referring to the figures by characters of reference, 1 designates a tubular housing of thin sheet metal or other suitable material substantially elliptical in cross sectional contour. Opposed faces of this housing are cut away to provide openings 2 extending close 30 to the ends of the housing and to points near opposed edges thereof.

Removably mounted within the housing are strips of abrasive material indicated at 3 formed of sandpaper, carborundum paper or the like. Inserted between these strips is a wedging blade or core 4 tapered toward one end and having its opposed faces convexed transversely. The large end of this core may be provided with a handle 5 which,

with the housing 1, can be suitably ornamented.

In using the device either of the exposed portions of the abrasive strips is rubbed over the finger nails, the device being held by the handle 5. Should the abrasive strip become worn it can be removed readily by withdrawing the tightly wedged core 6, placing a new strip in position and reinserting the wedge.

The device can be made small enough to be conveniently carried in a handbag or the like.

What is claimed is:

1. A manicuring device including a housing having openings in opposed faces, strips of abrasive material in the housing and exposed through said openings, and a wedging core insertable into the housing and between said strips to constitute a backing for the strips.

2. A manicuring device including a housing having an opening in one face thereof, an abrasive strip removably mounted in the housing and exposed through the opening, and a wedging core insertable into the housing to constitute a backing for the strip and clamp the strip within the housing.

3. A manicuring device including a housing substantially elliptical in cross section and having an opening, an abrasive strip insertable in the housing and exposed through the opening, and a wedging core insertable into the housing to constitute a backing and a clamping means for the strip.

In testimony that I claim the foregoing as my own, I have hereto affixed my signature.

JOSEPH JORDAN RIGGSBEE.
